DAM

Filed April 30, 1930

UNITED STATES PATENT OFFICE

CALVIN V. DAVIS, OF MOUNT VERNON, NEW YORK, ASSIGNOR TO AMBURSEN CONSTRUCTION COMPANY, INC., OF NEW YORK, N. Y., A CORPORATION OF NEW YORK

DAM

Application filed April 30, 1930. Serial No. 448,535.

This invention relates to a novel and improved type of dam, and more particularly to a foundation structure adapted for use where the foundation material contains areas which are unsuitable for supporting the load of the dam. The invention will be best understood from the following description and the annexed drawings, in which I have shown a selected embodiment of the invention and in which:

Fig. 1 is a vertical sectional view through a dam constructed according to this invention.

Fig. 2 is a section on an enlarged scale, taken on the line 2—2 of Fig. 1.

At certain sites selected for the construction of dams there is frequently found an area or areas comprising foundation material not capable of taking the full loading put upon it by the dam structure. Such areas frequently occur at portions of a site which is otherwise of excellent material for dam construction. Examples of such areas are furnished by rock, which is different in character from the high-grade rock adjacent to it or rock which may be broken or have lines of cleavage not capable of resisting the sliding forces put upon it by the weight of the structure; a faulted condition caused by earthquakes or major earth movements; or a deep narrow gorge filled with earth or other soft material which it would be uneconomical to excavate.

An example of a situation which may be found is shown in Fig. 2 wherein A designates a portion of soft material which may be found in the stream bed across which the dam is being built and which may extend downwardly for a great depth. Adjacent to this material may be found a portion B of broken rock capable of taking more load than the portion A but still not sufficiently good to support the dam structure. On opposite sides of the poor material A and B it is not uncommon to find sound rock areas C.

According to prior art practice, it has been the custom to bridge a fault such as that described above, by means of a reinforced beam or slab upon which the superstructure of the dam is placed. With such a construction,

however, when the load is applied to the slab or beam, there is apt to occur a differential in settlement because of the difference in character of the foundation material beneath the slab.

According to this invention, I span the faulty material with an arch barrel extending up- and down-stream over the fault and having abutments on opposite sides of the fault. In the selected embodiment, the dam is shown as having an up-stream water bearing deck 1 supported on a plurality of buttresses 2 extending down-stream from the deck. These buttresses are carried to solid rock wherever feasible, but where faulty material such as A and B may occur, I provide an arch barrel 3 having abutments on the solid rock on opposite sides of the fault.

This arch barrel is shown as being monolithic in character and poured integrally with the buttresses. Extending between the abutments of the arch barrel is a slab 4 which is tied integrally to the haunches of the arch adjacent the abutments, so as to form a chord tying together the opposite ends of the arch. To more effectively tie the slab to the arch barrel, suitable reinforcing 5 may be employed.

Not only does the slab 4 act as a chord, but it may also be used to support a certain amount of the load of the dam, this amount depending upon the character of the material A and B beneath it. To that end I provide on the slab piers 6, preferably disposed directly beneath buttresses 2 supported by the arch barrel, and these piers preferably have their tops disconnected from the intrados of the arch but contacting therewith at 7. Then, when the load is put on the arch barrel, it may deflect to a certain extent, and the deflection is resisted by the piers 6. Under some conditions, it may be advisable to connect the tops of the piers to the arch barrel.

These piers may extend lengthwise of the arch barrel, and extending between them and completely across the space beneath the barrel may be placed transverse partitions 8 which, with the piers and barrel, form a cellular structure, thus adding to the strength of the construction. The construction may

be still further strengthened by making the piers 6' nearest to the abutments integral with the barrel. If desired, transverse ribs 9 may be disposed above the barrel and extend between buttresses to solid rock on either side of the faulty material.

In order to prevent the building up of unequal pressure due to seepage of back water, the slab, piers and partitions may be provided with suitable drains 10.

I claim:

1. A masonry dam comprising an upstream deck supported by a plurality of buttresses extending downstream from the deck, and a foundation structure for some of said buttresses comprising an arch barrel extending up- and down-stream, with said buttresses resting on the extrados of the barrel, and piers disposed beneath the intrados of said barrel beneath said buttresses and forming substantial continuations of said buttresses.
2. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, piers disposed beneath the intrados of said barrel beneath said buttresses, and a slab on which said piers rest, said slab forming a chord connecting the haunches of the arch adjacent their abutments.
3. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, and piers disposed beneath the intrados of said barrel beneath said buttresses and disconnected from the barrel, but with the piers next the abutments of the barrel integral therewith.
4. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, piers disposed beneath the intrados of said barrel beneath said buttresses and disconnected from the barrel, and partitions extending transversely of the barrel between said piers.

5. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, piers disposed beneath the intrados of said barrel beneath said buttresses and disconnected from the barrel,

and partitions extending transversely of the barrel between said buttresses above the barrel.

6. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, piers disposed beneath the intrados of said barrel beneath said buttresses and disconnected from the barrel, and partitions extending transversely of the barrel between said piers and between said buttresses above the barrel.

7. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, piers disposed beneath the intrados of said barrel beneath said buttresses and disconnected from said barrel, and a slab on which said piers rest, said slab forming a chord connecting the haunches of the arch adjacent their abutments.

8. A masonry dam comprising an upstream deck supported by a plurality of buttresses extending downstream from the deck, a foundation structure for some of said buttresses comprising an arch barrel extending up- and down-stream, with said buttresses resting on the extrados of the barrel, and piers disposed beneath the intrados of said barrel beneath said buttresses and disconnected from the barrel.
